UNITED STATES PATENT OFFICE.

NATHANIEL B. WALES, OF BOSTON, MASSACHUSETTS, ASSIGNOR, BY MESNE ASSIGNMENTS, TO SELAW PRODUCTS COMPANY, OF SAGINAW, MICHIGAN, A CORPORATION OF MICHIGAN.

COMBINED VEHICLE LAMP AND HORN.

1,185,740.

Specification of Letters Patent.

Patented June 6, 1916.

Application filed October 18, 1912. Serial No. 726,538.

To all whom it may concern:

Be it known that I, NATHANIEL B. WALES, a citizen of the United States of America, residing at Boston, in the county of Suffolk 5 and State of Massachusetts, have invented certain new and useful Improvements in Combined Vehicle Lamps and Horns, of which the following is a specification, reference being had therein to the accompanying drawings.

In the present state of the art, motor vehicle accessories are so numerous that their convenient disposition upon the car is often a serious problem. Furthermore, these accessories where external to the body, break the contour lines and interfere with the simplicity and beauty of design.

It is the object of the present invention to simplify the design by combining in a single unit the lamp and the horn, which, as usually mounted, form separate projections from the body.

To this end the invention consists broadly in the association of said parts, and further 25 in the construction by which both instruments are inclosed in a common casing of simple design without impairing the efficiency of either.

In the drawings: Figure 1 is a longitudinal section through one form of my combined lamp and horn. Fig. 2 is a front elevation thereof. Figs. 3 and 4 are similar views to Figs. 1 and 2, showing a modified construction.

35 A is a lamp provided with the usual parabolic reflector B, at the focus point of which is an illuminant such as an electric bulb C.

D is a sound-producer of any suitable construction, but, as shown, is one which is electro-magnetically operated. The detail construction of this sound-producer forms no part of the present invention, but as indicated in the drawings, E are the electro-magnets; and F the vibratory armature, carrying the central striker-pin, which impinges against a diaphragm H to produce the sound. It is usual to provide such sound-producers with horns or megaphones, which intensify the volume of sound. With my combined 45 construction, this megaphone is formed adjacent to the wall of the parabolic reflector, and may either entirely surround said reflector, as shown in Figs. 3 and 4; or only a segment thereof, as shown in Figs. 1 and 2. In each

case the necessary expanding chamber is 55 formed without materially altering the usual contour lines of the lamp case. Thus in the construction shown in Figs. 1 and 2, the segmental case I, which forms the horn or megaphone, resembles the hood which is frequently used in gas lamps for the escape of the products of combustion. The electro-magnetic sound-producer is placed in a rearward extension J of the case without materially changing the contour lines thereof, 65 or increasing the size to any appreciable extent. With the construction shown in Figs. 3 and 4, the space between the parabolic reflector and the outer casing K forms an expanding chamber for the megaphone, 70 and the annular front which surrounds the lens L may be perforated, as at M, to permit the passage of sound.

What I claim as my invention is:

1. The combination with a lamp having a 75 concave reflector, of a sound-producer arranged in rear of said reflector, a casing surrounding said sound-producer and reflector, extending to the front of the latter, the space between said casing and said reflector 80 being substantially unobstructed, and a perforated front plate between said reflector and casing, connecting said members and forming the sound outlet.

2. The combination with a lamp having a 85 parabolic reflector, of a sound-producer arranged in rear of said reflector, a casing surrounding said sound-producer and reflector and forming with said reflector an unobstructed space, and a perforated ring connecting the front end of said reflector and casing. 90

3. The combination with a lamp having a 95 concave reflector, of an electro-magnetically operated sound-producer arranged in rear of said reflector, and an unobstructed expanding chamber or megaphone, forming an outlet for the sound and arranged adjacent to said reflector.

4. The combination with a lamp having a 100 parabolic reflector, of a casing surrounding said reflector, and forming therewith a substantially unobstructed space having a perforated front, and sound-producing means housed within said casing. 105

5. The combination with a lamp having a parabolic reflector, of a casing conforming to the general lines of said reflector and extend-

ing in rear thereof and forming therewith an unobstructed space, and a sound-producer housed within said casing.

6. The combination with a lamp having a concave reflector, of an electro-magnetically operated sound producer arranged in rear of said reflector, and a segmental case surrounding a portion of said reflector, the space between said metallic case and the

reflector forming an unobstructed outlet for 10 the sound.

In testimony whereof I affix my signature in presence of two witnesses.

NATHANIEL B. WALES.
